DRAG LINE EXTENSIBLE BOOM

Henry C. Hughes, deceased, late of Tulsa, Okla., by Lillie V. Hughes, administratrix, Tulsa, Okla.

Application May 4, 1953, Serial No. 352,832

3 Claims. (Cl. 212—144)

The invention relates to extensible booms, particularly adapted for excavating where a drag bucket is moved inwardly and outwardly for dragging dirt into a trench or the like, particularly along a right of way, where it is necessary to utilize a relatively long boom.

A further object is to provide an extensible boom comprising inner and outer telescopically engaged members, and to provide cable supporting means for the boom, and extending over a plurality of sheaves on the upper side of the boom as a whole for bracing the relatively long boom when extended.

A further object is to provide the inner end of the outer boom section with a lug extending downwardly through an elongated slot in the under side of the inner boom section, and cable means connected to said lug and extending over a sheave carried by the outer end of the inner boom section and leading to a boom extending winch.

A further object is to provide a slide block within the outer boom section and extending upwardly through a longitudinal slot in the outer boom section, and around which slide block sheave one of the loops of the boom supporting cable extends. The slide block assumes a position in engagement with the outer end of the inner boom section at all times for supporting purposes.

A further object is to support the boom by a single cable having one of its ends anchored to the outer end of the outer boom section, and extending over multiple sheaves and over the sheaves on the boom and leading to a boom supporting winch.

With the above and other objects in view the invention resides in the combination and arrangement of parts as hereinafter set forth, shown in the drawing described and claimed, it being understood that changes in the precise embodiment of the invention may be made within the scope of what is claimed without departing from the spirit of the invention.

In the drawing:

Figure 1 is a view in side elevation of the extensible boom showing the same supported on a conventional form of tractor.

Figure 2 is a top plan view of the boom showing the same in extended position.

Figure 3 is a vertical transverse sectional view taken on line 3—3 of Figure 1.

Figure 4 is a vertical transverse sectional view taken on line 4—4 of Figure 1.

Figure 5 is a detail perspective view of the slide block and a portion of the extension beam.

Figure 6 is a bottom perspective of the inner end of the extension boom section, showing a portion of the inner boom section.

Figure 7 is a detail top plan view of the multiple sheaves over which the boom supporting cables extend.

Referring to the drawing, the numeral 1 designates an end view of a conventional form of tractor, and 2 a supporting bracket extending upwardly from the tractor and in which is mounted a support 3 for the boom, and the multiple sheave block 4. Mounted on the upper side of the tractor is boom supporting and adjusting winch 5.

The inner boom section 6 is preferably tubular and rectangular in cross section, and has its inner end hinged connected at 7 to the support 3. The inner end of the outer boom section 8 is slidably mounted in the inner boom section 6, and is preferably rectangular in cross section as shown in Figure 6. Extending downwardly

2

from the inner end of the boom section 8 is a lug 9, which lug extends through the elongated slot 10 in the under side of the inner boom section 6. Connected to the lug 9 is an extension cable 11, which cable extends outwardly and over a fixed sheave 12, and thence rearwardly towards the tractor and over a boom extending winch 13.

By operating the winch 13 the outer boom section 8 can be extended as desired. The extension operation preferably takes place when the outer end of the boom is resting on the ground.

Mounted on the tractor 1 is a drag out winch 14 which controls a cable 15. Cable 15 extends outwardly and over a sheave 16 carried by the outer end of the extension boom 8, and then extends downwardly and connected to a conventional form of drag bucket 17. By manipulating the winch 14, the bucket can be moved outwardly to the full line position shown in Figure 1, after the bucket has previously been pulled inwardly by the drag in cable 18, which cable is controlled by the drag in winch 19 on the tractor. Various positions assumed by the bucket are shown in dotted lines in Figure 1, as well as the inner and outer positions of the extension boom 8.

25 In relatively long extension booms, it is necessary to provide means for supporting and bracing the boom at a plurality of points along its length, and at the same time provide a movable or travelling support substantially intermediate its length to get a maximum extension and a minimum retraction. To accomplish this result the upper side of the inner boom section 6 is provided with a sheave 20 intermediate its ends, and the outer boom section is provided with a sheave 21 intermediate its ends.

30 Slidably mounted within the outer boom section 8 is a slide block 22, a portion of which block extends through an elongated slot 23 in the upper side of the outer boom section 8, and is provided with a sheave 24 above the boom sections. Block 23 is disposed between blocks 20 and 21, and being a travelling type, no matter how far the outer boom section is extended by the cable 11, it will be stopped in its inner position by engagement with the outer end 6a of the inner boom section when the slack is taken up on the supporting cable

connected to the lug and extending over said last named sheave and means for imparting a pull on said cable for extending the boom sections.

2. A device as set forth in claim 1 including, a travelling block slidably mounted within the outer boom section, the upper side of said outer boom section having an elongated slot, said block having a portion extending through the slot a sheave carried by said portion of the slide block and disposed above the outer boom section, said supporting cable having one of its loops extending over said last named sheave and forming means whereby said block will be maintained in engagement with the outer end of the inner boom section at all times no matter how far the outer boom section is extended.

3. A device as set forth in claim 1 wherein the sheaves carried by the upper side of the boom comprise a sheave spaced from the inner and outer ends of the inner boom

section, a sheave carried by the outer boom section and spaced from its inner and outer end and a sheave slidably mounted on the outer boom section and adapted to engage the outer end of the inner boom section at all extended positions of the extensible boom.
